DESIGN FOR A MOTORCYCLE

Orley Ray Courtney, Lansing, Mich.

Application July 16, 1940, Serial No. 93,719

Term of patent 3½ years

To all whom it may concern:

Be it known that I, Orley Ray Courtney, a citizen of the United States, residing at Lansing, in the county of Ingham and State of Michigan, have invented a new, original, and ornamental Design for Motorcycles, of which the following is a specification, reference being had to the accompanying drawing, forming part thereof.

Fig. 1 is a top plan view of a motorcycle showing my new design.

Fig. 2 is a side elevational view thereof; and
Fig. 3 is a front elevational view.

I claim:

The ornamental design for a motorcycle, as shown.

ORLEY RAY COURTNEY.
